UNITED STATES PATENT OFFICE.

EDWIN BOSSHARDT, OF EMMENBRÜCKE, NEAR LUCERNE, SWITZERLAND.

FURNACE FOR MELTING METALS.

1,164,983.

Specification of Letters Patent. Patented Dec. 21, 1915.

Application filed December 28, 1914. Serial No. 879,335.

To all whom it may concern:

Be it known that I, EDWIN BOSSHARDT, a citizen of the Republic of Switzerland, residing at Emmenbrücke, near Lucerne, Switzerland, have invented new and useful Improvements in Furnaces for Melting Metals; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15. The known open hearth furnaces are of the reverberatory type and they have a gas firing and gas and air chambers arranged beneath the furnace. These chambers act as preheating chambers and the gas and air 20 stream from these chambers through flues, provided in the furnace-heads or ends into the melting-room, where they mix and where they are burned up. It has also been proposed to provide, near each end of such reverberatory furnace, a gas-generator and to 25 guide the gas produced in these generators and the preheated air through the end walls of the furnace into the melting room, where they can mix and where they are burned up. In these two kinds of open hearth furnaces the gas and the air stream through 30 slots provided in the head or end walls into the melting room. These slots are disposed in such a manner that the gas streams into the melting room near its middle and the air near its two ends, or the gas streams in 35 near the lower level and the air near the upper level of said room. However, in both instances a good and quick mixing of the gas and air does not take place and the gas is not 40 wholly burned up, so that it may come into contact with the furnace charge. For this reason it was not possible to attain in the hitherto open hearth furnaces a sufficient 45 high melting temperature.

In the production of very tough cast iron, particularly of cast steel used for casting pieces having very thin walls, for instance walls of only two millimeters thickness, it 50 has been found, that the material obtained in the hitherto known open hearth furnaces is not adapted for casting thin pieces. If the metal produced in such furnaces is used for casting pieces of large size the formation 55 of shrinking holes, or so called pipes, can-

not be prevented and upon a cooling of such cast pieces cracks will appear at the places where the thin and thick walls are joined. This proves, that the casting material has not been sufficiently tough and liquid. These 60 drawbacks are in consequence of the insufficient mixing of the gas and air and of the too low melting temperature resulting therefrom.

Hitherto the casting of very thin and complicated pieces could only be effected, in a satisfactory manner, by using crucible cast steel, the latter being more suitable for this purpose than the metal obtained by proceeding according to the different refining processes. It is, however, well known that the process for producing crucible cast-steel is 70 more expensive than the refining processes, (Bessemer, Thomas, or hearth refining processes).

It has, therefore, been proposed to improve the hearth refining process, which, with the exception of the process for producing crucibles, gives the purest material by raising the heat in the furnace in some 80 way or other to a higher degree, in order to obtain a material, which is not only very tough, but also sufficiently liquid. To this end it has been proposed to spray finely divided oils by means of nozzles into the furnace, but the results obtained were not satisfactory, as an admixture of oil has the effect of accelerating the crumbling of the brick-work, so that the whole process becomes very 85 unremonerative.

The object of the present invention is to provide a hearth-furnace of the Siemens-Martin or open hearth furnace type in which all the hereinbefore mentioned drawbacks are eliminated. The main feature of the 95 hearth furnace constructed according to my invention and provided in a known manner with gas-generators arranged adjacent to each furnace head or end and with gas outlet-openings arranged below the outlet openings for the preheated air, consists in the provision in each end wall of the furnace of at least one horizontal slot arranged below said gas outlet-openings and on the level of the white heat zone of the gas-generators 100 and connecting the generators with the melting room of the furnace.

A further important feature of my invention consists in the provision of at least one channel in each furnace head adapted to pre- 110

heat the gas produced in the generators before it streams into the melting room. In such a hearth furnace the gas streaming into the melting room comes to lie between the 5 broad layers of heated air flowing into said room and the flames streaming from the white heat zone of the coal firing into the melting room. In this manner the gas stream will be surrounded by said air layers 10 and said flames, so that it will be wholly burned up. The result of this is, that the temperature in the melting room will rise to a very high degree and that a very pure and tough melting product is obtained.

15 One mode of carrying the invention into effect is shown by way of example in the accompanying drawings, in which:

Figure 1 is a vertical longitudinal section through the furnace, Fig. 2 is a plan view 20 of the furnace showing partly a section on the line A—B of Fig. 1. Fig. 3 is a section on the line C—D of Fig. 1, and Fig. 4 is a section on the line E—F of Fig. 1.

In the embodiment of the invention shown 25 in the drawings, 1 denotes the hearth or melting room, and 2 the two head ends of the furnace. The generators 3 are arranged adjacent these heads 2 and the grates 4 of the generators are charged by means of the 30 loading hoppers 5. Beneath the grates 4 there are arranged in a known manner the air distributors 6 supplied with compressed air through the pipes 7, by a blower not shown in the drawings.

35 8 denotes air chambers arranged beneath the hearth 1 and adapted to preheat the air. For this purpose they are built as regenerators acting in the same manner as the regenerators of the known open hearth or 40 Siemens-Martin furnaces. Channels 9 connect these chambers 8 to the furnace-heads 2, the ends of these channels being arranged in the upper part of the heads 2 forming vaulted and downwardly directed slots 9', 45 so that the hot air streams in at the uppermost level of the melting room 1. The chambers 8 are also connected by means of channels 10 to a chamber 12 provided with a butterfly valve 11. A channel 13 connects, 50 the chamber 12 with the chimney and a channel 14 connects said chamber with the atmosphere (Fig. 2).

Channels 15 provided in the furnace-heads 2 connect the upper end of each gas generator 3 with regulating boxes 16 provided with valves 17 adapted to close the openings communicating with the horizontal preheating channels 18. In each furnace head 2 there is provided such a channel 18. The 60 outlet openings 19 of these channels 18, through which the gas produced in the generators streams into the hearth room 1, are arranged beneath the slots 9'. Pipes 20 connect the regulating boxes 16 of one head of 65 the furnace with the boxes of the head on

the other side of the furnace. The two valves 17 disposed on the same side of the furnace are operatively connected by means of a device, which consists of levers 21 provided with counter-weights and engaging 70 the valve rods, a rod 22 connecting these levers and a hand lever 23 provided on this rod, (Figs. 1, 3, and 4). Between each gas generator and the melting room 1 there is provided on the level of the white heat zone 75 of the generators a horizontal slot 24 arranged beneath the two corresponding gas outlet openings 19.

25 denotes working openings and 26 the trough communicating with the tap-hole. 80

The process of melting a metal, for instance, cast-steel, in the hereinbefore described furnace may be carried out as follows: The butterfly valve 11 is alternately reversed in such a manner that at one time 85 the fresh air streaming through the channel 14 passes through the channel 10 disposed on one side of the furnace, the corresponding chamber 8, the corresponding channels 9 and the slot 9' into the melting room 1, where it 90 comes into contact with the charge and passes then through the slot 9' and the channels 9 arranged on the other side of the furnace, the chamber 8, channel 10, chamber 12, and chamber 13 into the chimney. 95 The heating gases streaming through the last mentioned chamber 8 heat thereby the refractory bricks, which are so arranged that they inclose a number of holes between them (not shown in the drawing). Thus, 100 these bricks will become red hot. At another time the air streams in a reversed direction through the furnace, whereby it is heated while streaming through the last mentioned chamber 8 and the gases leaving 105 the furnace heat the other chamber 8, so that, when the fresh air streams at first again through this chamber 8, it will be heated. From the foregoing it is evident, 110 that the air streaming into the hearth room 115 1 is always preheated.

The two gas generators 3 are simultaneously started. The gas produced in these generators streams through the channels 15 into the regulating boxes 16. Upon a reversal of the air supply from one side of the furnace to the other side the gas supply has also to be reversed, *i. e.*, one of the generators 3 has to be connected directly with the hearth, while the gas supply from the other generator to the hearth has to be interrupted. To this end I correspondingly open alternately the gas passage connecting the boxes 16 with the gas preheating channel 18 and the openings 19 of the furnace side on which the preheated air passes through the slot 9' into the hearth by raising the corresponding valves and I cut off at the same time the gas stream flowing from the boxes 16 through the channel 18 and the 125 130 135

openings 19 provided on the other side of the furnace by closing the corresponding valves 17.

The gas produced in the generator, which is not in direct communication with the hearth, streams through the pipes 20 into the two boxes 16 provided on the other side of the furnace, from where it passes together with the gas produced in the generator on this side through the corresponding channel 18 and the openings 19 into the hearth or melting room 1, and since the channels 18 preheat this gas, it will be heated to a high degree when it streams into said room.

The generators are filled with coal, and heat flows continually from the white-glowing coal through the slots 24 from below into the melting room 1. The superheated fresh air streams into the room 1 near the uppermost level and the flames produced in the white-glowing coal zone streams in near the lower level of said room, while the preheated gas passing through the head of the furnace streams in near the middle of the melting room 1. In this manner the gas is wholly inclosed by the superheated air and the thin flames of the white-glowing coal zone. Thus, a very good mixture of gas and air is obtained, which is immediately ignited, the gas being thereby completely consumed. The result of this is, that the temperature in the furnace will rise to 2000° C. and more. Owing to this very high melting temperature an absolutely pure and tough material is obtained; in other words, the steel produced is very poor in carbon, so that it is very tough. In the hereinbefore described hearth furnace, the gas never comes in a pure unmixed condition into contact with the furnace charge.

Such a furnace may, therefore, also be used for producing mild steel or ingot iron and weld iron. In this latter case the generators 3 are not quite filled with carbon, so that a part of the fire gases streams directly through the slots 24 into the hearth room 1. The hereinbefore described open hearth furnace may, however, as well be used for melting malleable iron, cast iron, and bronze. In a hearth furnace of the hereinbefore described type mild steel and cast steel may be produced as well by proceeding according to the acid process as by proceeding according to the basic process.

While the starting of an open hearth or Siemens-Martin furnace of the known open type requires 10 to 14 days, the temperature at which the charge may be introduced being attained only after this time, the furnace according to this invention may be made ready in about three days for receiving the first charge. Owing to the fact, that a small charge of 1000 to 1500 kilograms is introduced, the material may be heated to a

higher degree than is the case, if a great charge is introduced, so that it becomes very liquid. The result of this is, that the molten metal can be poured very quickly into the molds so that even very complicated castings having walls of only three millimeters thickness can be very well cast. This is not possible if the metal is melted in a furnace of a greater size. Into a furnace of the hereinbefore described type there may be introduced and melted at least four charges during twenty-four hours.

The advantages obtained by providing the hereinbefore mentioned slots 24 may be best deduced from the fact, that in a furnace adapted to receive a charge of 1000 to 1500 kilograms the heat streaming from the white-glowing coal of the generators 3 into the melting room 1 raises the temperature in the latter to about 1600° C.

As I have already stated, the channels 18 provided in the heads of the furnace and adapted to preheat the gas replace the pre-heating chambers used in the hitherto known open hearth furnaces (Siemens-Martin furnaces).

What I claim is:

1. An open hearth furnace comprising a melting room, a gas generator adjacent the latter and having a direct heat radiating connection between said room and the white heat zone of the generator.

2. An open hearth furnace, consisting of a melting room, in combination with gas-generators arranged adjacent each furnace head, air regenerators, air-passages connecting each of said regenerators with the melting room, at the hearth level means forming a direct communication between the white heat zone of the generators and the melting room and means to guide the gas produced in the generators into the melting room.

3. An open hearth furnace consisting of a melting room, in combination with gas-generators arranged adjacent each furnace head, air-regenerators, air-passages in the furnace-heads and connecting each of said regenerators with the melting room, a passage in each furnace-head forming a direct communication between the white heat zone of the generators and the melting room and channels adapted to guide the gas produced in the gas-generators into the melting room, the outlet openings of these channels being arranged below the outlet openings of the air-passages and above said passages provided in the furnace heads for transmitting the heat of the white heat zone.

4. An open hearth furnace, consisting of a melting room, in combination with gas-generators arranged adjacent each furnace head, air-regenerators, air passages in the furnace heads and connecting each of said regenerators with the melting room, a horizontal slot in each furnace head arranged

on the level of the white heat zone of the generators and adapted to put this zone into communication with the melting room, and channels adapted to guide the gas produced in the gas-generators into the melting room, the outlet openings of these channels being arranged below the outlet openings of the air passages and above said horizontal slots.

10 5. An open hearth furnace, consisting of a melting room, in combination with gas-generators arranged adjacent each furnace head, air regenerators, air passages in the furnace heads and connecting each of said regenerators with the melting room, a horizontal slot in each furnace head arranged on the level of the white heat zone of the generators and adapted to put this zone into communication with the melting room, 15 channels adapted to guide the gas produced in the gas generators into the melting room, the outlet openings of these channels being arranged below the outlet openings of the air passages and above said horizontal slots, 20 and means adapted to preheat the gas supplied by the gas-generators before it passes into the melting room.

6. An open hearth furnace, consisting of a melting room, in combination with gas-generators arranged adjacent each furnace head, air-regenerators, air passages in the furnace heads and connecting each of said regenerators with the melting room, a horizontal slot in each furnace head arranged 30 on the level of the white heat zone of the generators and adapted to put this zone into communication with the melting room, gas-channels in each furnace head communicating with the gas-generators, and a horizontal gas preheating channel in each fur- 35

nace head connected with said gas channels and having several passages communicating with the melting room, these passages being arranged below the outlet openings of the air passages and above said horizontal slots. 45

7. An open hearth furnace, consisting of a melting room, in combination with gas-generators arranged adjacent each furnace head, air regenerators, air passages in the furnace heads and connecting each of said regenerators with the melting room, a horizontal slot in each furnace head arranged on the level of the white heat zone of the generators and adapted to put this zone into communication with the melting room, 50 gas channels in each furnace head communicating with the gas generators, a horizontal gas preheating channel in each furnace head connected with said gas channels and having several passages communicating 55 with the melting room, these passages being arranged below the outlet openings of the air passages and above said horizontal slots, and means adapted to control the connection between the gas channels and the preheat- 60 ing channel of each furnace head.

8. An open hearth furnace comprising a melting chamber, a gas generator chamber adjacent the latter and a direct straight passage way connecting the white heat zone 70 of the generator and melting chamber for the purpose of supplying radiant heat of said zone to the melting chamber.

In testimony that I claim the foregoing as my invention, I have signed my name 75 in presence of two subscribing witnesses.

EDWIN BOSSHARDT.
